UNITED STATES PATENT OFFICE.

GERHARD DEHARDE, OF WIESBADEN, GERMANY.

DEVICE FOR ELECTRICALLY CONNECTING RAILS.

SPECIFICATION forming part of Letters Patent No. 697,817, dated April 15, 1902.

Application filed January 11, 1900. Renewed October 15, 1901. Serial No. 78,700. (No model.)

To all whom it may concern:

Be it known that I, GERHARD DEHARDE, a subject of the German Emperor, residing at Wiesbaden, in the Empire of Germany, have 5 invented a new and useful Device for Electrically Connecting Rails, of which the following is a specification.

My invention relates to a new and improved device for electrically connecting the adjacent ends of rails of an electric railway, thereby greatly increasing their efficiency for conducting the current.

My invention is also applicable for electrically connecting the twin rails or the guard-rail and main rail for conducting the current about a joint in the latter.

In the accompanying drawings, in which similar letters of reference refer to similar parts throughout, Figure 1 is a horizontal section of two rails electrically connected by my invention. Fig. 2 illustrates the conductor I employ. Fig. 3 is a vertical cross-section of twin rails connected to each other and also showing the conductor. Fig. 4 shows the conductor employed for connecting the twin rails. Fig. 5 is an end view of the conductor shown in Fig. 4. Fig. 6 is a section on the line $x-y$ of Fig. 4. Fig. 7 shows the conductor as illustrated in Fig. 4 wedged home. Fig. 8 is a diagram illustrating the use of the conductor.

From the drawings it will be seen that when the rails to be electrically connected lie end to end I employ a wire or arm C of copper extending parallel to the rails and overlapping each a predetermined distance and fastened at each end by an especially-constructed conductor or binder, which latter embraces the essential feature of my invention. On the other hand, where the rails to be connected are parallel to each other the wire C is omitted, the binder alone making the necessary connection.

As is known, fault has been found with the present manner of connecting, inasmuch as they are liable to become loosened through the vibrations given the track by passing trains, while also the current is poorly conducted, a considerable part escaping. With the object, therefore, of eliminating these disadvantages I have perfected the following invention:

Where end-to-end rails are to be connected, I employ, as stated, an arm C, the ends of which are flattened or formed into ears c' c^2 , 55 or these ears may have the wire C soldered thereto. Each of these ears is provided with a circular opening registering with circular holes a and b , formed in the rails. A binder is especially constructed for joining this conducting-arm and rails. Said binder comprises a hollow cylindrical body provided on the one end with an annular flange d , (see Fig. 1, left side,) while the other end is closed and slotted. The ear and binder are assembled as 60 shown in Fig. 1, left side, whence an iron or steel bolt E is driven in and through, breaking open the slotted end of the said binder (see Fig. 1, right side) and turning the flaps backward. The bolt is always of a slightly-greater 65 diameter than the interior of the binder, so that when it is driven in the binder (made of copper) is expanded and wedged at every possible point against the rail and ears c' or c^2 , (or, as shown, directly against the rail.) 70 75

Where twin rails are connected for carrying the current, I employ three binders. (See Fig. 8.) Here the current, passing from the right to the left, leaves rail F and is conducted by binder 2 to rail G, where it travels 80 past the joint in rail F and returns to the latter by binder 3, &c., or by omitting binder 3 the successive rails G or F may be alternately joined to their respective successive followers by the arm C aforesaid. In all cases, however, where parallel rails are to be connected I employ the same binder slightly modified and best shown at H in Figs. 3 to 7. Here, as illustrated, the body of the binder is lengthened to a length approximately the distance 85 between the rails, while formed on each end is a neck h and h' , adapted to pass through openings in the rails. One end of the binder has an annular flange, as aforesaid, while a similar flange is formed at the base of the 90 binder by neck h' . The body of the binder in this instance is provided with slits h^4 and wedged home in place by bolts I and K. Bolt I being first driven in breaks open the slotted end, (see Fig. 5,) which is protruding 95 through rail f, and expanding neck h' , and driving back the flaps rivets it firmly in place. Bolt K is then driven in, and as the opening in the binder is somewhat smaller than the 100

opening in the neck h the bolt expands, the binder spreading the slots h^4 open and driving the body into the swelled form shown in Figs. 3 and 7. By this binder it is shown that 5 first they are absolutely wedged into place, preventing thereby any loosening through the vibrations caused by passing trains, while the binder is wedged most compactly at all points against the rails, the flanges gripping on one 10 side of the rail and the driven-out flaps on the other, thus affording a great contact-surface, thereby increasing the conductibility for the current.

Having now described my invention, what 15 I claim as new, and desire to protect by Letters Patent, is—

1. A new and improved electrical conductor for connecting rails, and comprising a binder formed hollow with one end normally closed 20 and slotted, said binder being adapted to be wedged home in suitable holes formed in the said rails affording an increased surface of contact for conducting the current and insuring permanency of the said binder in position, 25 substantially as described.
2. In a new and improved binder for elec-

trically connecting rails for conducting a current the combination of a cylindrical hollow body adapted to pass through holes provided in said rails, an annular flange on one end of said binder-body, a slotted normally closed end in said other end and a bolt adapted to be driven into said binder expanding the same and wedging it firmly and permanently in place, substantially as described. 30

3. In a new and improved binder for electrically connecting rails for conducting a current, the combination of a hollow cylindrical, slotted body, a neck formed on each end thereof, a flange on one end of said binder, a connecting slotted web, ears thereon and bolts adapted to be driven into said binder and wedge the same permanently into place affording a large contact-surface for the current, substantially as described. 40

In witness whereof I have hereunto set my hand in presence of two witnesses.

GERHARD DEHARDE.
